INVENTOR:
JAMES ROBERT ROBERTSON.

PER. *L. L. Russin*

ATTORNEY.

UNITED STATES PATENT OFFICE

JAMES ROBERT ROBERTSON, OF LONDON, ENGLAND

SCREEN FOR COLOR PHOTOGRAPHY

Application filed January 11, 1928, Serial No. 246,055, and in Great Britain January 22, 1927.

This invention relates to improvements in and relating to screens for color photography and in particular to the projection of moving pictures in colors.

According to the present invention a number of color screens are provided between the projecting apparatus and the viewing screen, and each color screen comprises a vacuum chamber containing a different gas, adapted to assume for example a red, green and blue color respectively when an electron discharge is passed through the gas in the vacuum chamber. The electrodes in each chamber are in circuit with circuit closing and opening means operable from the projecting apparatus, the electrodes of the several chambers being put in circuit in turn so that first, say, a screen of a red color is formed, next a screen of blue color, and so on. The vacuum chambers may also contain mixtures of gases which will assume various desired colors when an electron discharge is passed.

One or more of the vacuum chambers may be surrounded by an annular vacuum chamber also containing a gas or a mixture of gases and also adapted to assume a color when an electron discharge is passed therethrough, and the electrodes of these annular chambers are likewise connected with circuit making and breaking devices controlled by the projecting device. The color assumed by the gas in the annular chamber has a modifying effect upon the color assumed by the chamber within the annular chamber.

The color screens are preferably mounted in a tubular member and the tubular member may also carry one or more optical lenses.

In addition to having a screen of the above type varying in color as desired, the source of light used for projection may comprise a group of vacuum tubes containing different gases so that the color of said

source of light may be varied in accordance with that of the screen.

In the accompanying drawings,

Fig. 1 illustrates diagrammatically in sectional elevation one form of construction of the color screen according to the present invention.

Fig. 2 illustrates diagrammatically a moving picture projection system in accordance with the invention.

Fig. 3 illustrates in front elevation switching means for the vacuum chambers of the invention which are operable by the film driving mechanism.

Fig. 4 is a sectional elevation on line 4-4 of Fig. 3.

In Fig. 1, E is a tube of metal, within which are mounted three vacuum chambers C, C¹, C², in alignment. In the construction illustrated the three chambers are of cylindrical form. Surrounding each chamber C, C¹, C² are arranged annular vacuum chambers F, F¹, F². All the vacuum chambers contain a gas or a mixture of gases, the chamber C containing for example neon, which on the passing of an electron discharge therethrough will become red in color, C¹ may be a chamber of uranium glass or ordinary glass coated with Willimite and containing CO₂ which will produce a fluorescent green color, and C² containing argon, which will give a blue color. The annular chambers F, F¹, F² also contain gases adapted, on the passing of a discharge, to assume a color which will modify by its propinquity the color in the chamber C, C¹ or C². For example the annular chamber F may contain hydrogen or another gas which assumes an orange hue, so that the red of the gas in chamber C becomes tinged with orange.

In each chamber C, C¹, C² are electrodes G, G¹, G², and in each annular chamber F, F¹, F² are electrodes H, H¹, H², and these electrodes are all in circuit with a current supply and the circuits to each pair of elec-

trodes is made or broken by mercury switches D, D¹, D². These switches are operated by, or synchronously with the mechanism which advances the film step by step in the projector in the manner described below in connection with Figs. 3 and 4. Thus for one picture, switch D is closed and vacuum chamber C is converted into a red screen by the discharge passed therethrough; 5 for the next picture switch D is opened and switch D¹ closed, converting chamber C¹ into a green screen; and so on. The switches D, D¹, D² may operate simultaneously the vacuum chambers C, C¹, C² and the annular 10 chambers surrounding them, or if the chambers C, C¹, C² only are being used the switches D, D¹, D² may be single switches.

Combined with the chambers C, C¹, C², 15 may be used any suitable optical lenses A, B, which may be apo-chromatic lenses sealed 20 to the ends of the chambers for directing the light rays coming through the film, through the color screens on to the viewing screen.

25 In Fig. 2, the source of light for projecting the pictures on the screen may be a group of vacuum tubes J containing different gases, in circuit with mercury switches N, N¹, N², so as to throw beams of colored 30 light in turn on a discharge passing through the tubes aided by the reflector I, through light condensers K, on to and through the film L and thence through a shutter O and a device M similar to the screen device 35 described above in connection with Fig. 1. When a film has a picture opposite the shutter opening, of an object which has been photographed, for example, through a red screen or has been photographed when flooded 40 with red light. The switch N puts in circuit one of the series of tubes J producing red light, and simultaneously a gaseous screen in the device M which only permits red light to pass. The red elements in the 45 object are thus shown on the screen. On the next picture being presented before the shutter opening, the switch N is opened and the switch N¹ puts in circuit other tubes J giving, say, a green light, and simultaneously the green gaseous color screen in device M is excited and so on.

50 Instead of the vacuum tube device J a source of white light may be employed which is not affected by the switches N, N¹, N². Again a source of white light may be used in combination with the vacuum color tubes.

The switches N, N¹, N² are operated by 55 the film advancing sprocket T, which is driven through intermittent gearing in known manner by a motor. The operation of the switches is illustrated in greater detail in Figs. 3 and 4. The switches N, N¹, N² are pivotally mounted at their rear ends 60 on a shaft P and are adapted to be moved

up and down about the shaft by means of connecting rods S, S¹, S² and eccentrics R, R¹, R² respectively. The latter are mounted on a shaft W which is driven from the film sprocket T by means of gear wheels U, V. The arrangement is such that one switch at a time is depressed at its front end. This causes mercury contained in the switch to flow into the front end thereof and make contact between two wires X (or X¹ or X² as the case may be) and thus switch in one of the vacuum chambers. In the position illustrated in Figures 3 and 4, switch N¹ is shown in the closed position and switches N and N² are shown in the open position.

What I claim is:

1. A color screen device for use in connection with moving pictures comprising a plurality of gas discharge chambers aligned 85 and each adapted to assume a different color upon electrical excitation and means for exciting said chambers in turn.

2. A color screen device for use in connection with moving pictures comprising a plurality of gas discharge chambers each adapted to assume a different color upon excitation, a gas discharge chamber of substantially annular form surrounding at least one of said first named chambers and adapted 95 to assume a color upon electrical excitation, and means whereby all of said chambers can be excited in turn.

3. In a motion picture projector for projecting pictures in color, a plurality of gas discharge chambers aligned and each adapted to assume a different color upon electrical excitation, electrodes mounted in said chambers, means whereby an electric potential can be applied to said electrodes in turn, an 100 optical lens in alignment with said chambers, and a sleeve wherein said chambers and optical lens are mounted.

4. In a motion picture projector for projecting pictures in color, a plurality of gas discharge chambers aligned and each adapted to assume a different color upon electrical excitation, a gas discharge chamber of substantially annular form surrounding at least one of said first named chambers and adapted 115 to assume a color upon electrical excitation, electrodes mounted in all of said chambers, means whereby an electric potential can be applied to said electrodes in turn, an optical lens in alignment with said first named chambers and a sleeve wherein all of said chambers and said optical lens are mounted.

5. A moving picture projection system 125 for projecting pictures in color comprising a projection light source, a light condenser, a picture film, means for advancing said film, an optical lens, a color screen comprising a plurality of gas discharge chambers each adapted to assume a different color 130

upon electrical excitation and switches, operable by said means for advancing the picture film, adapted to control the excitation of said chambers.

- 5 6. A moving picture projection system according to claim 5, wherein said projection light source comprises a plurality of gas discharge tubes each adapted to assume a different color upon electrical excitation
10 and adapted to be excited in synchronism with the gas discharge chambers of the color screen.

In testimony whereof I have signed my name to this specification.
